PRINTING INSTRUMENTALITY FOR
TYPEWRITING MACHINES

Frank H. Trego, New York, N. Y., assignor, by
mesne assignments, to Ralph C. Coxhead Cor-
poration, New York, N. Y., a corporation of
Delaware

Application March 24, 1931, Serial No. 524,815

12 Claims. (Cl. 197—49)

This invention relates to improvements in type-writing machines and more particularly to printing instrumentalities therefor. The invention is shown as applied to the varityper writing machine which includes a type carrier or shuttle settable by the operation of the key levers and with which co-operates a printing hammer to effect the printing on a work sheet.

An object of the invention is to facilitate the operation of the printing instrumentalities and also to render the printing mechanism practically noiseless.

In carrying out the invention the printing is accomplished by pressure instead of impact as heretofore. To this end there is provided means including a toggle to actuate an element which presses the work-sheet against the types of the shuttle.

To actuate the toggle there is provided a solenoid connected in a normally open electric circuit which may be closed by a switch operable by the key levers to effect energization of the solenoid to thus actuate the pressure element, of the printing instrumentalities, which co-operates with the type shuttle.

A feature of the invention relates to means for adjusting the toggle in accordance with the number of sheets being manifolded and in accordance with the different sizes of types on the various shuttles which may be used.

Another feature of the invention relates to means to limit the motion of the actuating mechanism for the pressure element.

Other features and advantages will hereinafter appear.

In the accompanying drawings which form part of the specification,

Fig. 1 is a sectional side view of the machine.

Figure 2 is a detail view illustrating means for adjusting the printing element in accordance with the number of sheets to be manifolded.

Fig. 3 is a rear view of the machine, some of the parts being omitted.

Fig. 4 is a view showing the printing instrumentalities operated.

Fig. 5 is a fragmentary rear view of the escapement mechanism and the switches associated therewith.

Fig. 6 is a view of the wiring diagram.

Similar reference characters represent similar parts throughout the several views.

The machine includes a main frame 10 provided with a track 11 upon which is supported a carriage 12 to travel back and forth through the medium of anti-friction balls or rollers 13. The

carriage is provided with feed rollers 14 and 15 by which a work sheet 16 may be fed upwardly between a type carrier or shuttle 17 and a co-operating or pressure element 18, the latter being located behind the work-sheet.

The type shuttle 17 is located in front of the work sheet and is supported on an anvil 20 secured to a shaft 21 suitably supported by a cross-bar 22 and a plate 23 on the machine frame. The shuttle 17 is actuated by a lever 24 connected to said shuttle by an upwardly extending finger 25 engaging a fin 26 on the shuttle, which fin extends through a slot 27, in the anvil 20, the fin serving also to support the shuttle on the anvil.

The shuttle actuating lever 24 is secured to a sleeve 28 rotatably supported on the shaft 21 and bearing on the cross bar 22. The lever 24 may be actuated in either direction from a central position, by means fully illustrated in my application, Serial No. 495,872, filed Nov. 15, 1930. Said means includes two levers 30, only one of which is shown herein, secured to the upper ends of vertically disposed rock-shafts 31 supported at their upper ends by a fixed bracket 32 and at their lower ends by fixed brackets 33. Springs 30^a hold the levers 30 in their normal positions where they are arrested by suitable stops (not shown).

As the rock shaft 31 is actuated, in the direction of arrow (Fig. 1) a pin 34 on the lever 30 engages the shuttle lever 24 to actuate the latter about the axis of the shaft 21 to thus actuate the type shuttle 17 to carry the selected one of the types 35 to the printing point. The element 18 is then operated in a manner hereinafter described to print on the work-sheet.

Before the printing takes place, however, the selected type is accurately positioned at the printing point by an indexing device or stop 46, there being one associated with each key-lever 48, and actuatable thereby, against the action of a return spring 47, to project the upper end into the path of an arm 49 of the shuttle actuating lever 24.

Each rock shaft 31 is actuated by an electro-magnet or solenoid 50 comprising a sucking coil 51 and a plunger 52; the coil 51 on the left hand side of the machine, when energized, drawing the plunger 52 thereinto to actuate an arm 53 on the right hand side of the machine, secured to shaft 31. The shaft is thus rotated to effect the actuation of the shuttle actuating arm 24 as previously described.

The solenoids 50 are connected in an electric circuit including a source of energy 55 (Fig. 6)

connected to a ground 56 and a conductor 57 which is connected to the solenoids 58. A conductor 58 extends from each solenoid 58 to a normally open switch 59 comprising a fixed contact 60 and a movable contact 61, the contact 60 being connected to a conductor 62 to the ground 56. A main switch 63 is provided for connecting the machine with source of energy 55. Thus it will be understood that by closing either of the switches 59 the associated solenoid 58 is energized to operate the associated rock shaft 81, on the opposite side of the machine, and thereby actuate the type shuttle 17 in one direction or the other from its central position as previously described.

15 The key levers 48 are divided into two sets, one set at each side of the middle of the machine, each set having associated therewith a universal bar 65 forming a portion of a frame 66 supported for independent movement on a shaft 67 while being actuated by the rear ends of the key-levers.

20 The movable contact 61 of the switch 59 is supported on a bracket 70 (Fig. 1) and is insulated therefrom, said bracket being secured to the frame 66 by a screw 71. As the frame 65 is actuated, by the key levers, the contact 61 is carried upwardly therewith into engagement with the contact 60, thus closing the switch to effect the energization of the solenoid 58 to actuate the type shuttle until it is arrested by the lever 24, 25 the arm 49 thereof contacting with the operated indexing pin or stop 46.

25 The contacts 60 of the switches 59 are each supported in a block 72 of insulating material secured to the frame of the machine by screws 73.

30 Either of the universal bars 65 is actuatable still further, after its switch 59 is closed, to effect actuation of the carriage escapement and the actuation of the co-operative printing element 18 in a manner hereinafter described. To permit 35 this further movement of the universal bars the contacts 60, of the switches 59, are each movable against the action of a spring 72^a contained within the block 72.

35 The carriage 12 is connected by the usual rack 45 75 with a pinion 76 of the carriage escapement 78 which is actuatable by either of the universal bars 65. To this end the universal bar frames 66 have each a cross-bar 77 engaging an arm 78 secured to the shaft 67 to rock the latter. Said 40 shaft 67 has secured thereto a rearwardly extending arm 79 which, when actuated, operates a dog rocker 80 about its pivot 81 (Fig. 5) to carry a fixed dog 82 into the path of an escapement wheel 83 supported on a shaft 84, the escapement wheel 50 having the usual one-way driving connection (Fig. 1) including a spring-pressed pawl 86^a, on a disk 86 rotatably supported on the shaft 84 and integral with the pinion 76; the pawl 86^a engaging a ratchet 87 secured to the escapement 55 shaft 84. The carriage is urged leftward of the machine by the usual means including the spring drum (not shown) which is connected to the carriage 12 by the strap 85; the action of said 60 spring drum tending to rotate the escapement wheel in a clockwise direction (Fig. 5) through medium of the pawl 86^a and ratchet 87.

65 After the dog 82 has entered the path of the teeth of the escapement wheel a loose dog 88 is 70 swung, about its pivot 89, out of engagement with said escapement wheel 83, by an arm 92 having a slot 93 into which extends a pin 94 from said loose dog. Upon the release of the loose dog, from the escapement wheel, it is carried upwardly by a frame 95 pivotally supported on the escapement shaft 84, said frame being actuated by the

printing element 18 through the medium of a connecting pin 96, the element 18 being operated in a manner hereinafter described.

5 The pawl 88, as it is carried upwardly, is guided by the slot 93 and is swung back into the path of the next adjacent tooth of the escapement wheel by the dog rocker upon its return movement so that, upon the rotation of the escapement wheel, subsequent to its release from the dog 82, the escapement wheel returns the loose dog to normal, thus completing a letter feeding 10 movement of the carriage.

15 The means to actuate the printing element 18 includes a solenoid 100 (Fig. 1) which is connected with the source of power 55 (Fig. 6) by a conductor 101 and the conductor 57; the solenoid 100 being also connected in series with a normally open switch 102 and a normally closed switch 103 by conductors 104 and 105, respectively; the switch 103 being connected to the 20 ground 56 by a conductor 106.

25 The switch 102 includes a relatively fixed contact 107 supported in a block 108 of insulating material secured (see Fig. 5) to the main frame 10 by screws 109. The switch 102 further includes a contact 110 supported in a block 111 of insulating material secured to the dog rocker 80 so that when the latter is actuated, as previously described, the contact 110 is carried downwardly against the contact 107 to close the circuit in 30 which the coil 112 of the solenoid 100 is connected, to energize the latter.

35 Upon the energization of the coil 112 a plunger 113 is sucked thereinto to actuate the co-operative printing element about its fulcrum 114 (Figs. 1 and 4); the plunger 113 being connected by suitable means, hereinafter described, to the element 18. After the printing operation the solenoid 100 is de-energized, in a manner described 40 later, and the co-operative element 18 is then restored to normal by means including a spring 115. The feeding movement of the carriage, through the medium of the pin 96, which connects the element 18 with the dog carrying frame 95 of the escapement mechanism, may assist in 45 returning said element to normal.

50 The operation of the printing instrumentalities is rendered noiseless, and to this end the co-operative printing element 18 does not have the action of a hammer, as formerly or in other words 55 does not print by impact, but has a pressing action against the shuttle 17, produced by means including a toggle 120 which slows down the motion of the element 18 as it approaches its printing position, so that the said element 18 meets the shuttle without any noise and with great pressure.

55 The toggle 120 includes two links 121 and 122 pivotally connected to each other by a stud 123; the link 121 being supported by a pivot 124 on a bracket 125 secured to an extension 126 of a bracket portion 127 supported on the machine frame 10 by a forward extension 128.

60 The other link, 122, of the toggle is pivotally connected to the element 18 by a pin 129. The toggle is operable by the solenoid 100, and to this end the plunger 113 of the solenoid is connected by a resilient link or spring 130 to a lever 131 to swing the latter downwardly about a pivot 132 on the bracket 126. The free end of said 65 lever pulls downwardly on a link 133 to swing a lever 134 downwardly about a pivot 135 on a fixed bracket 126. Said lever 134 is connected by a link 137 to the stud 123 which connects the toggle links 122 and 123 so that as the lever 134 is 70 75

swung downwardly from the position in Fig. 1 the toggle 120 is straightened out to the position in Fig. 4 to press the element 18 against the type shuttle 117.

5 It will be observed, in Fig. 4, that the point of connection 123 of the toggle links 121 and 122 is quite close to, but has not reached the dead center, or, in other words, is not quite in alignment with the centers of the pivots 124 and 129, 10 as indicated by the straight line 140. Thus it will be understood that when in the printing position of the toggle there is still pressure of the element 18 against the type shuttle 17.

Suitable noiseless means are provided to limit 15 the downward movement of the toggle. For this purpose there is provided a toggle 145 comprising links 146 and 147 connected to each other by a pivot 148. The link 146 is pivotally connected by a pin 149 to the bracket 126 and the link 20 147 is connected by a pivot 150 to the lever 131 so that as the latter is actuated by the plunger 113 the motion of said lever is limited by the straightening out of the toggle 145. A spring 151 may be connected to the link 147 to move the 25 toggle 145 off the dead center as the toggle 120 and its actuating parts are restored to normal by the spring 115 connected to the link 121.

The toggle supporting bracket 125 may be secured to the fixed bracket 126 by a screw 155; 30 said screw passing through the elongated slot in the bracket 125 so that said bracket may be shifted slightly, fore and aft of the machine, to adjust the toggle 120 to produce the desired pressure of the printing element 18 against the 35 shuttle 17.

Instead of rigidly securing the bracket 125 to the bracket 126, there may be provided a shoul- 40 dered screw 156 (Fig. 2) to hold said bracket on the bracket 126 so that it may be slid freely fore-and-aft of the machine to adjust the toggle to vary the operated position of the printing element in accordance with the number of sheets, in a pack, to be manifolded. A screw 157 held fore-and-aft of the machine by a bracket 158 is 45 threaded into the bracket 125 and may be manipulated by a head 159 to shift the bracket 125 and thus adjust the toggle 120 to vary the operated position of the printing element 18 in accordance with the thickness of the paper and the 50 number of sheets to be manifolded.

The screw head 159 may be provided with suitable indices 160^a co-operating with a fixed pointer 160 to assist in adjusting the bracket 125.

To de-energize the solenoid 100, after printing, the switch 103 is automatically opened as in my above mentioned application. Said switch includes, for this purpose, a fixed contact 165 on a block 166 of insulating material (Fig. 5) mounted on a bracket 167 secured to the main frame 10. 55 Co-operating with the contact 165 is another contact 168 supported on a bell-crank lever 169 pivoted, by a screw or stud 170, on the bracket 167. A detent spring 171, secured to the bracket 167, acts through the medium of a roller 172 60 on one side of a nose 173 of the bell crank lever 169 to hold the switch closed as in Fig. 5.

The operation of the switch 103, to open it, is initiated by the printing element 18, during its actuation to the printing point, through the medium of the dog carrying frame 95; said frame being provided with a lug 175 which engages a finger 176 of the bell crank or switch lever 169 to swing the latter about its pivot 170 in a clockwise direction (Fig. 5) until the point of the 75 nose 173 wipes past the roller 172 of the spring

detent 171. The contact 168 is pressed axially by a spring 168^a and is slidably supported on the switch lever 169 so that the switch may remain closed during the early part of the actuation of the switch lever 169.

5

The printing of the element 18 takes place before the spring detent 171 becomes effective to complete the actuation of the switch lever 169 to open the switch 103. Instantly after the printing, however, the switch is opened by said detent and 10 the solenoid is thus de-energized, thus permitting the printing element 18 to be restored to normal, by the springs 115 and 151.

While the printing element 18 is returning the finger 115 on the dog carrying frame engages a 15 finger 177 to initiate the return movement of the switch lever 169, said return movement being completed by the spring detent 171 acting on the nose 173 of said switch lever. Before the closing of the switch 103 is effected, the switch 102, controlled by the dog rocker 80, is opened.

While certain preferred embodiments of the invention have been shown it should be understood that changes in the form, arrangement, proportions, sizes and details thereof may be made without departing from the scope of the invention as defined in the appended claims.

I claim:—

1. In a typewriting machine, the combination of 30 printing instrumentalities including two elements, namely a single type carrier having a complete font of types and an element to co-operate therewith, to act against any one of the types to print, key levers, means operable by said key levers to selectively set the type carrier to register the de- 35 sired type at the co-operative element, means to pivotally support said co-operative element, a toggle to be straightened out and acting on the active end of the co-operating element to swing it about its pivot to press it against the type car- 40 rier to effect printing on a work sheet, intermediate means to operate said toggle, an electro-magnet to actuate said intermediate means, and means to noiselessly arrest the intermediate 45 means.

2. In a typewriting machine, the combination of 50 printing instrumentalities including two elements, namely a type carrier and an element to co-operate therewith, means to selectively set the type carrier to register the desired type at the co-operative element, means to pivotally support 55 said co-operative element, a toggle including two elements, a pivoted connection between said toggle elements, a fixed fulcrum for the end of one toggle element, a pivotal connection between the other toggle element and said co-operative element, means including an operating lever, a link connecting the lever to said toggle, and means to actuate said operating lever.

3. In a typewriting machine, the combination 60 of printing instrumentalities including two elements, namely a type carrier and an element to co-operate therewith, means to selectively set the type carrier to register the desired type at the co-operative element, means to pivotally support said 65 co-operative element, a toggle including two elements, a pivotal connection between said toggle elements, a fixed fulcrum for the end of one toggle element, a pivotal connection between the other toggle element and said co-operative element, 70 an operating lever, a link connecting the operating lever with said toggle, power means, and means connecting the power means with said operating lever.

4. In a typewriting machine, the combination 75

- of printing instrumentalities including two elements, namely a type carrier and an element to co-operate therewith, means to selectively set the type carrier to register the desired type at the co-operative element, means to pivotally support the co-operative element, means including a lever to operate said co-operative element key-levers, means operable by the key-levers to effect the operation of said lever, a toggle independent of the operating means and connected to said lever to function only to limit the actuation of said lever, and a spring connected to the limiting toggle to restore it to normal.

5. In a typewriting machine, the combination of printing instrumentalities including two elements, namely a type carrier and an element to co-operate therewith to print on an interposed work sheet, means to selectively set the type carrier to register the desired type at the co-operative element, a toggle to actuate one of said elements to print against the other, electric means to actuate said toggle, a carriage, escapement mechanism for said carriage, key-levers, a universal bar operable by said key-levers to actuate the escapement, and a switch operable by said escapement to effect the actuation of the electric means to operate said toggle.

6. In a typewriting machine, the combination of printing instrumentalities including two elements, namely a type carrier and an element to co-operate therewith, means to selectively set the type carrier to register the desired type at the co-operative element, a toggle to actuate one of said elements to print against the other, electric means to actuate said toggle, a carriage, escapement mechanism for said carriage, key-levers, a universal bar operable by said key-levers to actuate the escapement, a switch operable by said escapement to affect the actuation of the electric means to operate said toggle, a second switch operable by the escapement to render the electric means ineffective, and means to return the toggle and the associated element.

7. In a typewriting machine, the combination of printing instrumentalities including two elements, namely a type carrier and an element to co-operate therewith, means to selectively set the type carrier to register the desired type at the co-operative element, means to pivotally support said co-operative element, a toggle including two elements, a pivoted connection between said toggle elements, a fixed fulcrum for the end of one toggle element, a pivoted connection between said co-operative element and said co-operative element, means including an operating lever, a link connecting the lever to said toggle, means including an electro-magnet to actuate said operating lever, a carriage escapement, and means operable by said escapement to effect the actuation of said electro-magnet.

8. In a typewriting machine, the combination of printing instrumentalities including two elements, namely a type carrier and an element to co-operate therewith, means to selectively set the type carrier to register the desired type at the co-operative element, means to pivotally support said co-operative element, a toggle including two elements, a pivoted connection between said toggle elements, a fixed fulcrum for the end of one toggle element, a pivoted connection between the other toggle element and said co-operative element, means including an operating lever, a link connecting the lever to said toggle, means to actuate the operating lever, key levers, means operable by any one of the key levers to effect the actuation of the lever operating means.

9. In a typewriting machine, the combination of printing instrumentalities including two elements, namely a type carrier and an element to co-operate therewith, means to selectively set the type carrier to register the desired type at the co-operative element, means to pivotally support said co-operative element, a toggle including two elements, a pivoted connection between said toggle elements, a fixed fulcrum for the end of one toggle element, a pivoted connection between the other toggle element and said co-operative element, means including an operating lever, a link connecting the lever to said toggle, reciprocable power means to actuate said lever, and means to noiselessly arrest the power means.

10. In a typewriting machine, the combination of printing instrumentalities including two elements, namely a type carrier and an element to co-operate therewith, means to selectively set the type carrier to register the desired type at the co-operative element, means to pivotally support said co-operative element, a toggle including two elements, a pivoted connection between said toggle elements, a fixed fulcrum for the end of one toggle element, a pivoted connection between the other toggle element and said co-operative element, means including an operating lever, a link connecting the lever to said toggle, reciprocable power means to actuate said lever, and means to noiselessly arrest the power means.

11. In a typewriting machine, the combination of printing instrumentalities including two elements, namely a type carrier and an element to co-operate therewith, means to selectively set the type carrier to register the desired type at the co-operative element, means to pivotally support said co-operative element, a toggle including two elements, a pivoted connection between said toggle elements, a fixed fulcrum for the end of one toggle element, a pivoted connection between the other toggle element and said co-operative element, means including an operating lever, a link connecting the lever to said toggle, reciprocable power means to actuate said lever, means to arrest said lever in its effective position, and resilient means connecting the power means with said lever to absorb the shock produced by the power means when the lever is arrested.

12. In a typewriting machine, the combination of printing instrumentalities including two elements, namely a type carrier and an element to co-operate therewith, means to selectively set the type carrier to register the desired type at the co-operative element, means to pivotally support said co-operative element, a toggle including two elements, a pivoted connection between said toggle elements, a fixed fulcrum for the end of one toggle element, a pivoted connection between the other toggle element and said co-operative element, means including an operating lever, a link connecting the lever to the pivotal connection between the toggle elements, means to actuate the operating lever, key levers, and means operable by any one of the key levers to effect the actuation of the lever operating means.

13. In a typewriting machine, the combination of printing instrumentalities including two elements, namely a type carrier and an element to co-operate therewith, means to selectively set the type carrier to register the desired type at the co-operative element, means to pivotally support said co-operative element, a toggle including two elements, a pivoted connection between said toggle elements, a fixed fulcrum for the end of one toggle element, a pivoted connection between the other toggle element and said co-operative element, means including an operating lever, a link connecting the lever to said toggle, means to actuate the operating lever, key levers, means operable by any one of the key levers to effect the actuation of the lever operating means, the extent of movement of said lever being constant, and means to adjust the position of the fixed pivot to vary the pressure of the printing element independently of the lever actuating means.
